FORMATION OF METAL STRIP UNDER
CONTROLLED PRESSURES

Joseph B. Brennan, Cleveland, Ohio

Application August 12, 1948, Serial No. 43,881

8 Claims. (Cl. 29—18)

1

This invention relates to the formation of continuous or elongate, metal strips, especially to the formation of such metal strips under controlled pressures, usually appreciably below atmospheric.

Metallic strips made in accordance with the teachings of the invention are particularly suitable for use in the manufacture of electric condensers although they may be used in any desired manner.

In the formation of metal strips of the above class, one method of forming such strips is to spray metal continuously onto a moving base strip and solidify such metal onto the base strip so as to form a continuous metal strip from the deposited metal. Formation of uniform metal strips that have desirable electrical properties is difficult since the sprayed metal tends to form strips which are not of the same gauge throughout. Furthermore, sometimes it is difficult to obtain the degree of porosity or density desired in such metal strips. Also, excessive oxidation is frequently present and the degree of fineness of spray is ordinarily difficult to regulate, in atmospheric spraying operations.

The general object of the present invention is to provide a novel, effective method of producing elongate metal strips or metal layers of uniform composition and electrical properties.

Another object of the invention is to deposit sprayed metal particles onto a base strip with the spraying and depositing action occurring under subatmospheric pressures.

A further object of the invention is to deposit sprayed metal particles uniformly in a completely controlled atmosphere.

A further object of the invention is to control the temperatures of sprayed metal particles and to control the temperature of a base strip onto which the metal particles deposit.

Another object of the invention is to utilize increased pressure differentials in spraying molten metal.

A further object of the invention is to provide a metal strip made from spray deposited metal particles which is free from entrapped gases.

The foregoing and other objects and advantages of the invention will become apparent as the specification proceeds.

Attention is directed to the accompanying drawing wherein:

Fig. 1 discloses a vertical section of one form of apparatus for practicing the invention; and

Fig. 2 is a fragmentary section taken on line 2—2 of Fig. 1.

The present invention is a continuation in part of my copending application entitled Method of and Apparatus for Spraying Metal, Serial No. 548,023, filed August 4, 1944, and now abandoned.

The specific apparatus disclosed herein is de-

2

scribed in more detail in a copending application Serial No. 1,926, filed January 13, 1948, by Robert M. Brennan, wherein such apparatus and its use is claimed.

5 The structure shown in the drawing includes an enclosed chamber 10 in which is positioned a metal storage pan or crucible 11, which has an extension spout 12 provided thereon. An inverted container 13 is positioned over a portion 10 of the metal storage pan 11 and is supported thereby. The inverted container 13 is adapted to receive a supply of molten metal 14 therein and retain same at a different level from metal in the extension spout 12. This action is effected by means of an outlet 15 that is formed in the container 13 adjacent the extension spout 12 of the pan 11. Any conventional means are associated with the outlet 15 so as to regulate the flow of the molten metal therethrough. In 15 this instance, a float type of valve is provided for maintaining the metal 14 at a predetermined level in the spout 12 and such device includes a gate valve 16 that has a lug 17 extending outwardly therefrom. The gate valve 16 is positioned within the container 13 and seals the outlet 15 when the valve is seated on the inner surface of the container 13 adjacent the outlet 15. A float 18 is provided and is carried on the metal 14 in the extension spout 12. This float 18 connects through a lever arm 19 to the lug 17 on the gate valve 16. A pin 21 extends through the lever arm 19 and pivotally secures it to an extended portion of the container 13. Thus as the level of the molten metal in the extension spout 12 20 falls below a predetermined value, the float 18 will cause the valve 16 to be opened slightly and metal from the supply chamber will flow into the spout to maintain the metal level therein substantially constant even though metal may be 25 intermittently or continuously withdrawn therefrom.

The container 13 may be supplied with a storage ladle 22 which is positioned within the container and is controlled from the outside of the container by means of a control arm 23. The control arm 23 may be extended to a point beyond the confines of the chamber 10, if desired, so that, in all events, metal can be placed inside of the inverted container 13 through a trap feed tube 24 provided for the container and such molten metal may be stored in the ladle 22 and added intermittently to the pool of metal retained in the container 13.

55 The foregoing apparatus will maintain a constant or uniform pressure head of molten metal in the extension spout 12 and any type of spray device may be associated with or connected to the extension spout 12 so as to be supplied with a uniform pressure source of molten metal. In 60 this instance a nozzle 25 is shown secured to the lower surface of the extension spout 12. This

nozzle 25 has a plurality of gas passageways 26 formed in the end portion thereof and a tube 27 may connect thereto for supplying gas to the passageways 26 which discharge the gas immediately adjacent and converging upon the bore 28 of the nozzle 25 at the end of the nozzle. In some instances the tube 27 will not be used.

In order to control the temperature of the molten metal prior to its ejection from the nozzle 25, an induction heating coil 29 may be positioned around the inverted container 13 while a second induction heating coil 31 may be positioned around the nozzle 25. Hence by supplying high frequency electrical energy to the coils 29 and 31 any desired temperature or fluidity of the material therewithin may be set up by variation of the amount of heating current provided to such coils. Of course, the pan 11, container 13 and nozzle 25 are formed from a conventional material, usually refractory, so as to remain unaffected by any heating energy supplied to the metallic material 14.

In case the metal 14 should overflow from the extension spout 12 for any reason, it will pass over a lip 32 formed on the spout 12 and be caught in a receptacle 33 from which a pump 34 will force the material back into the container 13 through a conduit 35.

A salient feature of the present invention is that the spraying or deposition of the molten metal 14 occurs under a vacuum. Hence a vacuum pump 36 connects to a lower section 10a of the chamber 10 and serves to set up a desired vacuum within such chamber section. Thus the metallic material in the extension spout 12 is subjected to a desired pressure whereas the deposition of such metal also occurs under a desired sub-atmospheric pressure. Production of a continuous metal strip from the sprayed metal particles is facilitated by means of a backing strip 37 that is led by the nozzle 25 so as to receive all metal particles ejected therefrom. The backing strip 37 is shown as being originally stored on a roll 38 and as passing to a final storage roll 39. The backing strip 37 may be made from any desired material and one very satisfactory substance is a thin, soft, porous strip of paper whereas matted fibers also might be used in some instances and other desired backing materials may be used. In some instances wherein a porous metal strip with no backing material carried thereby is desired, the backing strip 37 should be made from a smooth, highly polished metal, such as stainless steel, and such a belt is used in the drawings forming a part hereof. In such instance, the deposited metal particles would coalesce and combine as they are sprayed or deposited so as to produce a continuous uniform metal strip which would be on but not intimately bonded to the backing strip 37. After production of the sprayed metal strip, it could be separated from the backing strip 37 at any convenient time to provide a metal strip free from any objectionable backing material. In some instances where a paper or fibrous backing is used, it is possible to ignite the backing strip after it has been used to form a metal strip thereon and such combustion will effectively remove all or substantially all of the original backing material.

It may be desirable to control the temperature of the molten metal 14 as it moves from the nozzle 25 and diffuses out for deposit onto the backing strip 37. Hence a control funnel 41 is positioned adjacent the nozzle 25 for receiv-

ing the sprayed metal particles and another high frequency electrical heating coil 42 may be positioned around the control funnel 41 for control of the temperature of the metal particles as they move through the chamber 10 for deposit on the backing strip 37. Of course, the roll 39 is usually driven so as to move the backing strip 37 past the nozzle 25 at a desired rate to control deposit of metal onto such backing strip.

In some instances it may be desirable to vary or control the temperature of the backing strip 37. Hence any convenient temperature control means may be associated with the roll 38 or with a portion of the backing strip 37 as it leaves the roll 38 so as to heat or cool the backing strip to a desired temperature.

As best shown in Fig. 2, a cooling shoe 100 is provided for association with the under surface of the backing strip 37. This cooling shoe 100 is particularly adapted to be used when the backing strip 37 is formed from metallic material from which the deposited metal is to be thereafter separated in the form of a porous metal strip. The cooling shoe 100 has cooling fluid, usually water, supplied thereto through a tube 101 and an exhaust tube or conduit 102 also connects to the cooling shoe for exhausting cooling fluid therefrom. It will be noted that the upper surface of the cooling shoe 100 has a recess 103 formed therein in which the strip 37 is positioned.

As a special feature of the present invention, deposition of molten metal along the edges of the strip 37 is prevented by means of endless bands, or other suitable means, indicated at 104 and 105 which are adapted to overlie the edges of the strip 37 and move along therewith. These bands 104 and 105 may be positioned on rolls 106 and, if necessary, other guide rolls may be provided to prevent the bands from striking the guide tube or funnel 41 on the return stretch movement of the bands. Preferably a scraper 107 is provided to scrape undesired metal depositing onto the bands 104 and 105 from contact therewith. The roll 39 is shown provided for receipt of a stainless steel band 37 thereon. In some instances even though the stainless steel band is not used, and it is desired to heat or cool the deposition strip, the shoe 100 may have desired heating or cooling fluid associated therewith.

Of course, any desired drive means may be provided for the rolls 106. Normally the bands 104 and 105 should be driven at identically the same speed as the backing strip 37.

The drawing also shows that the backing strip 37 passes between a pair of rolls 43 and 44 after metal is deposited onto the backing strip. The rolls 43 and 44 may be positioned at any desired point adjacent the nozzle 25 to receive the backing strip after metal has been deposited thereon. The rolls 43 and 44 are provided to compress or compact and coalesce metallic particles on the backing strip to prevent gas entrapment in the deposited metal, which entrapment is also avoided by use of a vacuum atmosphere. Ordinarily the metal strip produced by the metal particles deposited through the nozzle 25 will be porous and the degree of porosity can be controlled by variation of the degree of vacuum within the chamber 10. The greater the vacuum, the slower is the cooling of the deposited particles and the slower the cooling of the deposited particles, the less the porosity of the resultant metal strip.

The metal strip may be heated to the point of vaporization and attain a mirror-like, continuous, dense metal in the strip, which heating may occur at any desired time.

While any desired material may be sprayed in accordance with the invention, the method is primarily provided for the formation of metal strips from aluminum or magnesium. Aluminum strips are particularly suited for use in the production of electrodes for electric condensers.

By practice of the present invention, a uniform metal deposit action can be realized to produce a uniform size metal strip which has uniform electrical properties.

As previously pointed out herein, any kind of apparatus may be used in the practice of the invention and likewise any desired operable size of apparatus may be used. The base strip may be formed of any desired composition and it is even possible to use a polished cylinder for deposit of sprayed material thereon with the strip produced being continuously removed from one portion of the cylinder while molten metal particles are continuously deposited on another portion of the moving cylinder which would be driven in a uniform manner.

Of course, only the end of the nozzle and the deposit means may be subjected to a vacuum if desired and any desired pressure, usually above atmospheric, may be set up in the chamber 10 by any desired type of apparatus. It also is possible to set up a different pressure in the container 13 than exists at other points within the chamber 10. Even hydraulic pressures in excess of 250 pounds per square inch in differential may be used in chamber 10 in relation to the spray section 10^a, and no atomizing gas as shown entering at 27 is needed, only the pressure and heat on the molten metal being utilized to make a fog or mist thereof as such molten metal is being deposited. The action of the metal when sprayed, will be at least partly dependent upon the nozzle design and any desired nozzle construction may be used.

In depositing metal in accordance with the invention it will be realized that the metal may be atomized, or vaporized, when in the process of deposition since the release of the heated metal into the vacuum through the nozzle 25 may cause such action, and this action may result regardless of whether a carrier gas is provided for the hot metal or not. By the pressure on the hot metal, a directional spraying of same, whether leaving the nozzle as a liquid or gas, can easily be effected. The spray action will be controlled by the temperature of the sprayed metal, the degree of vacuum in the chamber 10^a, the pressure in the chamber 10, and the design of the spray nozzle.

Usually the deposited metal is received upon a moving base strip but the invention is not limited to such deposition action.

While one complete embodiment of the invention has been disclosed herein, it will be appreciated that modification of this particular embodiment of the invention may be resorted to without departing from the scope of the invention as defined by the appended claims.

Having thus described my invention, what I claim is:

1. That method of depositing metal comprising the steps of liquefying a metal, applying a constant pressure to the metal, and spraying the metal under pressure into a reduced pressure atmosphere to aid in vaporization and atomiza-

tion of the sprayed metal while it is projected in a desired direction.

2. The method of producing an elongated metal strip comprising continuously depositing discrete molten metal particles from a uniform pressure head of molten metal onto a base member, and maintaining a partial vacuum on the molten metal particles during such deposition.

10 3. The method of producing an elongated metal strip comprising continuously depositing discrete molten metal particles from a uniform pressure head of molten metal onto a base member, maintaining a partial vacuum on the molten metal particles during such deposition, and compacting the deposited metal while retaining it under a partial vacuum.

20 4. The method of spray depositing a layer of molten metal comprising maintaining a constant head on a body of molten metal, depositing the metal on a base by spray discharging it from the body of metal toward the base, and maintaining a partial vacuum on the discharged metal during such deposition.

25 5. The method of uniformly spraying molten metal to form a composite strip comprising the steps of maintaining a constant head on a body of molten metal and a constant level of the molten metal, and continuously depositing metal onto a base strip by spray discharging it from the body of metal toward the base strip.

30 6. The method of forming an elongated metal strip comprising the steps of maintaining a constant head on a body of molten metal, continuously depositing the metal onto a base by spray discharging it from the body of metal toward the base, and continuously removing the spray-deposited layer of metal from the base as an elongated strip.

40 7. The method of forming an elongated metal strip comprising the steps of maintaining a constant head on a body of molten metal, continuously depositing the metal onto a base by spray discharging it from the body of metal toward the base, continuously removing the spray-deposited layer of metal from the base as an elongated strip, and controlling the exposed width of the base to regulate the width of the spray-deposited strip.

45 8. The method of forming an elongated metal strip comprising the steps of maintaining a constant head on a body of molten metal, continuously depositing the metal onto a base by spray discharging it from the body of metal toward the base, and continuously moving the base at a constant lineal speed past the spray of the molten metal whereby to form thereon a spray deposited layer which is of uniform thickness longitudinally of the base.
